INVENTOR:

Morris W. Greenstein,

BY

Geo. F. Maitz

ATTORNEY.

UNITED STATES PATENT OFFICE.

MORRIS W. GREENSTEIN, OF NEW YORK, N. Y.

DECORATIVE FABRIC.

Application filed April 3, 1925. Serial No. 20,396.

To all whom it may concern:

Be it known that I, MORRIS W. GREENSTEIN, a citizen of the United States, and a resident of the borough of Manhattan, city, county, and State of New York, have invented a certain new and useful Decorative Fabric, of which the following is a specification sufficient to enable others skilled in the art to which the invention appertains to utilize the same.

While applicable to decorative fabrics generally, and various other uses, the object of my invention is, primarily, to afford a novel and ornate parti-colored drapery suitable for lamp shades, curtains, and analogous purposes, in which the contrasted effect of colored patchwork is enhanced by perforate lines formed by the stitching by which the patchwork is united with the basic fabric, such stitching thus affording the double function of means of attachment and of rendering the fabric in a unitary sense transparent along the lines of the colored pattern or design involved, all as herein-after fully set forth, the invention consisting substantially in the specific combination and structure of parts described and claimed herein whereby the above recited effects are attained by means of hemstitching.

In the accompanying drawings I illustrate a practical embodiment of the essential features of my invention as exhibited in a portion of fabric of the character designated, it being understood of course that I do not limit myself to the pattern and details therein shown by way of exemplification, since infinite variety in design and coloring may be resorted to in adapting my new decorative fabric to various purposes and utilities without departing from the spirit and intent of my invention in this respect.

With this understanding:—

Fig. 1, represents a front view of a portion of a basic fabric decorated with patchwork of contrasted color hemstitched thereto to form perforate bordering and design;

Fig. 2, is a rear view of the portion of basic fabric shown in Fig. 1;

Fig. 3, is a section taken upon plane of line 3—3, Fig. 1.

B, is the basic fabric of any suitable textile material, embellished with patchwork P, of various colors. Thus, in Fig. 1, of the drawings, patches of three primary colors,

red, blue, and orange, indicated symbolically, are shown by way of example as attached to the basic fabric B, by hemstitching s, thereby creating perforate bordering or embellishment according to requirements or preference.

Obviously this perforate stitching s, may be utilized not only as a border to the patches P, but also may be incorporated with the patchwork within the border thereof and supplemental thereto, as indicated at s', in Fig. 1, of the drawings, when the character of the design renders such treatment desirable.

The transparent open lines of holes of the design created by the hemstitching greatly enhance the effective value of the colored patchwork fabrication, especially when the latter is interposed between light and the observer, so that my new decorative material is especially adapted for use in the formation of lamp shades, curtains, etc., the plural or multi-colored effects attainable being enhanced by the open work created by said stitching, which thus functions not only as a decorative adjunct to the colored patchwork, but also as the means of attaching such patchwork to the basic cloth.

It is to be understood that by the term "patchwork" as herein used I mean to designate ornamental "patches" so called, consisting of pieces of cloth superposed on the surface of a basic layer of cloth substantially as herein set forth.

What I claim as my invention and desire to secure by Letters Patent, is:—

1. As an article of manufacture, a decorative fabric of the character designated, comprising a base of textile material having imposed thereon patchwork united thereto by hemstitching constituting a perforate adjunct to the patchwork design, substantially in the manner and for the purposes set forth.

2. As an improved article of manufacture a decorative fabric adapted for the penetration of light therethrough, the same comprising a base of textile fabric, and patches of contrasting designs and colors superposed thereupon and united thereto by open-work stitches following the contour of such patchwork, the material embraced within said stitching being of multi-ply.

MORRIS W. GREENSTEIN.
